US00D608649S

(12) **United States Design Patent**
Rowland et al.

(10) **Patent No.:** **US D608,649 S**
(45) **Date of Patent:** **** Jan. 26, 2010**

(54) **BOTTLE WITH CAP**

(75) Inventors: **Aileen Rowland**, Sag Harbour, NY (US); **Lynne Florio**, New York, NY (US); **Anil Kalyanpur**, Edison, NJ (US); **John Cadenhead**, Jersey City, NJ (US)

(73) Assignee: **La Prairie, Inc.**, New York, NY (US)

(**) Term: **14 Years**

(21) Appl. No.: **29/330,677**

(22) Filed: **Jan. 12, 2009**

(51) **LOC (9) Cl.** **09-01**

(52) **U.S. Cl.** **D9/529**; D9/542; D9/573; D9/574; D9/435

(58) **Field of Classification Search** **D9/682, D9/686-687, 694, 516, 529-530, 541-546, D9/572-575, 435; D28/91.1; 215/381-385**

See application file for complete search history.
